(57) **CLAIM**

The ornamental design for a photographic media developer cartridge, as shown and described.

DESCRIPTION

The developer cartridge holds developer solution or fluid therein. The cartridge can be positioned at an appropriate location within a photographic image forming device to supply solution or fluid onto photographic media being developed in the device.

FIG. 1 is a front, top and right side perspective view of a photographic media developer cartridge in accordance with the invention; and,

FIG. 2 is a rear, bottom and left side perspective view of a photographic media developer cartridge in accordance with the invention.

1 Claim, 2 Drawing Sheets
